UNITED STATES PATENT OFFICE.

LOUIS H. HANSON, OF AUSTIN, TEXAS, ASSIGNOR OF ONE-HALF TO T. E. REASONOVER,
OF AUSTIN, TEXAS.

ADJUSTABLE AUTOMATIC VALVE REGULATOR.

Application filed December 27, 1923. Serial No. 683,058.

To all whom it may concern:

Be it known that I, LOUIS H. HANSON, a citizen of the United States, and resident of Austin, in the county of Travis, in the State 5 of Texas, have invented certain new and useful Improvements in Adjustable Automatic Valve Regulators, of which the following is a specification.

My invention relates to improvements in 10 valve regulators and it consists of the constructions, combinations and arrangements herein described and claimed.

An object of the invention is to provide 15 a device by means of which a valve in a pipe line may be opened quickly and by which said valve is reseated automatically at various adjustable speeds.

A further object of the invention is to 20 provide mechanism for a valve in a pipe line by which the valve is opened manually and reseated mechanically.

Other objects and advantages will appear 25 in the following specification reference being had to the accompanying drawing, in which—

Figure 1 is a perspective view of the automatic regulator on a valve of the globe type.

Figure 2 is a longitudinal section of the structure in Figure 1.

Figure 3 is a detail perspective view of 30 the combined intake and relief valve.

Figure 4 is a longitudinal section of the valve in Figure 3.

The invention is shown applied to a valve 35 of the globe type generally indicated 1. The valve may be situated in any pipe line, the fluid of which may be controlled in the particular manner described below. The valve member 2 is adapted to occupy a seat 3 from 40 which it is lifted by a stem 4 which carries the valve.

The elongated stem 4 of the valve member 2 passes through a closure cap 5 which has a cupped end 6 to coact with a similar cup 45 7 on the cylinder 8. The cup 7 has threads 9 by means of which it is screwed on the cup 6. The space or chamber provided by the cups is adapted to receive a packing.

Situated in the cylinder 8 is a piston 10 50 which carries a cup leather 11 in contact with the wall of the cylinder. The upper edge of the cylinder 8 terminates in a flange 12 beneath which the coupling 13 is swiveled. The coupling secures a base 14 on top 55 of the cylinder 8, and the base provides the

necessary closure for the cylinder. This base, however, does not make an airtight closure for the cylinder as it has a large opening 15 through which the air has free play and through which both the stem 4 and a 60 spring 16 operate. A gasket 17 is interposed between the flange 12 and the base 14, but this may be eliminated in actual practice if it be found that the coupling 13 will alone make a good connection.

At one side of the base 14 is a standard 18 which has a bracket 19 extending toward the center of the base. The bracket has a depending boss 20 in line with the opening 15. A cone-nut 21 which is adjustable on the 70 threads of the boss 20 provides the support for the upper end of the spring 16. This nut furnishes the base from which the spring presses toward the piston 10. The purpose of the spring is to keep the valve member 2 seated, and the tension of the spring is transmitted to the valve member through the piston 10 and valve stem 4. The valve stem is threaded at 22 to carry the nut by which the piston is supported in place.

A looped extension 24 of the standard 18 furnishes a guide for one end of the operating lever 25. This lever carries a lug 26 which provides a freely movable connection between the lever and the upper end of the 85 stem 4. The operating lever has pivotal mounting on the upper end of a link 27 which in turn is pivotally mounted in ears 28 on the base 14.

Fitted in the bottom of the cylinder 8 is 90 a sleeve 29 which has a kerf 30 at one side. This kerf is V-shaped as shown, and tapers from top to bottom so as to present an air escape opening of varying size. A ball check valve 31 gravitates on its seat at the upper 95 end of an air inlet 32.

This inlet communicates with a chamber 33 which is threaded at 34 at the upper end to receive a hollow plug. This plug prevents the ball check 31 from leaving the chamber 100 upon the admission of air into the cylinder 8. The lower end of the plug has several slots 35 which still let the air through should the ball check become seated against the lower end of the plug.

The valve sleeve 29 is screwed into a boss 36 at the bottom of the cylinder 8. The position of the sleeve, and the resultant size of the air opening at the kerf 30, determines the speed at which the piston 10 and valve 110

member 2 may return upon having been moved upward by the lever 25. A check nut 37 preserves the adjustments of the valve sleeve. A screw 38 in the loop 24 limits the 5 upward movement of the valve stem 4 by restricting the free end of the lever 25.

The operation will be readily understood from the foregoing description. The valve 2 is opened by pressing down on the right 10 end of the operating lever 25. The movement of the lever is limited by the screw 38. The stem 4 raises both the valve 2 and piston 10 against the tension of the spring 16.

Air is drawn into the bottom of the cylinder 8 through the valve sleeve 29, the ball 15 check 31 being unseated by the pressure of the inflowing air. Upon releasing the operating lever the spring 16 will force both the piston 10 and valve 2 back. However, 20 the rapidity of the return movement is governed by freedom with which the entrapped air in the cylinder 8 can escape at the kerf 30.

If the valve sleeve 29 is adjusted far into the base 36 so that but little of the kerf 25 shows, the escape of air will be slow and the return of the piston and valve will be slow. On the other hand, if the valve sleeve is adjusted far out of the base the area of the opening at the kerf will be large. The 30 escape of air will therefor be rapid and the return of both piston and valve will be rapid.

While the construction of the improved 35 automatic valve regulator herein described and claimed is that of a generally preferred form, obviously modifications and changes may be made without departing from the spirit of the invention and scope of the claims.

Having thus described the invention, what 40 I claim is:—

1. A device of the character described comprising a valve member having a stem, a cylinder through which the stem passes, 45 a piston carried by the stem fitting in the cylinder, an operating lever for manually unseating the valve and shifting the piston in the cylinder, means for returning both the piston and valve member, and a relief valve connected to the cylinder beneath the piston comprising an externally threaded sleeve having a ball check to rapidly admit air when the piston is shifted and a kerf to permit the slow egress of air when the piston 50 is returned to thereby retard the reseating of the valve member.

2. A device of the character described comprising a valve member having a stem, a cylinder through which the stem passes, 60 a piston carried by the stem fitting in the cylinder, means furnishing a guide for the stem, a spring carried by the stem, one end engaging the piston, means carried by said guide means abutted by the other end of the spring, an operating lever connected 65

with the stem for unseating the valve and raising the piston against the tension of the spring, a valve sleeve carried by the cylinder having a ball check for admitting air on said movement of the piston, and a kerf 70 at one side of the sleeve permitting the egress of air on the reverse movement of the piston under the influence of the spring.

3. A device of the character described comprising a valve member having a stem, 75 a cylinder through which the stem passes, a piston carried by the stem fitting in the cylinder, means furnishing a guide for the stem, a spring carried by the stem, one end engaging the piston, means carried by said guide means abutted by the other end of the spring, an operating lever connected with the stem for unseating the valve and raising the piston against the tension of the spring, a valve sleeve carried by the cylinder having a ball check for admitting air on said movement of the piston, and a kerf 80 at one side of the sleeve permitting the egress of air on the reverse movement of the piston under the influence of the spring, and means by which said sleeve may be adjusted in respect to the cylinder to expose 85 more or less of said kerf and correspondingly regulate the speed of reseating of the valve member. 90

4. A device of the character described comprising a valve member having a stem, a cylinder through which said stem passes, 100 a piston carried by the stem fitting in the cylinder, a spring to press down on the piston and seat the valve, an operating lever to manually shift the stem against the tension of the spring to unseat the valve, a sleeve having a ball check controlled inlet for admitting air into the cylinder beneath the piston on said shifting of the stem, a kerf at one side of the sleeve to provide egress for the air from the cylinder when the piston and valve member are returned by the spring upon release of the lever, said kerf being of outward tapering formation, and threads on the sleeve permitting adjustment thereof in respect to the cylinder to expose more or less of the kerf and thereby regulate the speed of reseating 110 of the valve member. 115

5. A device of the character described comprising a valve member having a stem, a cylinder through which the stem is passed, 120 a piston carried by the stem fitting in the cylinder, a base mounted on the cylinder having an opening through which the stem extends, a standard carried by the base having a bracket terminating in a boss which provides a guide for the stem, a spring surrounding the stem engaging the piston, means carried by the boss also engaged by the spring and forming an abutment therefor, an operating lever connected 125 to the stem, means on the base forming a 130

pivotal mounting for the lever when one end of the lever is depressed to raise the valve, means extending from the standard forming a guide for the other end of the lever, a sleeve having a check-controlled inlet for admitting air into the cylinder beneath the piston when the valve is raised, a V-shaped and tapering kerf at the side of the sleeve providing an air egress upon release of the lever and the return of the valve by virtue of said spring, and threads on the sleeve permitting adjustment thereof in respect to the cylinder to vary the size of the exposed portion of the kerf.

15 6. A device of the character described comprising a valve casing, a closure cap

having a cupped end, a cylinder surmounting the cap and having a complementary cupped end fitted on the aforesaid cupped end to provide a packing chamber, a valve in the casing having a stem passing through said chamber and cylinder, a piston carried by the stem and being operable in the cylinder, means for regulating the passage of air between the atmosphere and the interior of the cylinder beneath the piston, said means permitting a free unseating but retarded seating movement of the valve, and means embodied in and associated with said regulating means for governing the rate at which air may pass.

LOUIS H. HANSON.
